UNITED STATES PATENT OFFICE.

JOSEPH M. TOWNE, OF EAST ORANGE, NEW JERSEY, ASSIGNOR TO THE SAFETY CAR HEATING & LIGHTING COMPANY, A CORPORATION OF NEW JERSEY.

HOSE-CO尤PLING.

1,022,519.

Specification of Letters Patent. Patented July 16, 1912.

Application filed September 9, 1908. Serial No. 452,247.

To all whom it may concern:

Be it known that I, JOSEPH M. TOWNE, a citizen of the United States, residing at East Orange, in the county of Essex and State 5 of New Jersey, have invented certain new and useful Improvements in Hose-Couplers, of which the following is a full, clear, and exact description, such as will enable others skilled in the art to which it appertains to 10 make and use the same.

This invention relates to couplers, and more particularly to gravity couplers designed for use in connection with the steam heating apparatus of railway cars.

15 One of the objects of the present invention is to provide improved means for holding the complementary parts of a gravity hose coupler of the above character in locked condition during ordinary conditions of service, but which will permit automatic uncoupling when the hose is subjected to an undue or breaking strain, as when the cars draw apart with the parts of the coupler locked together. Other objects will be in part obvious and 20 in part pointed out hereinafter.

The invention accordingly consists in the features of construction, combinations of elements and arrangement of parts which will be exemplified in the construction herein- 30 after set forth, and the scope of the application of which will be indicated in the following claims.

In the accompanying drawings, wherein 35 is illustrated two of various possible embodiments of my invention, Figure 1 is a view in elevation of a coupler with the complementary parts in locked condition showing the same; Fig. 2 is a top plan view thereof; Fig. 3 is a view taken substantially on line 3-3 of Fig. 2; and Figs. 4, 5 and 40 6 are views corresponding respectively to views 1, 2 and 3 of a different embodiment of my invention.

45 Referring now to the drawings, and particularly to the embodiment illustrated in Figs. 1 to 3, inclusive, 1 represents the body portion of a gravity hose coupler broadly, one of the "Sewall" type, having the projecting side arm 2 which overlaps and engages 50 with the rigid lug or projection 3 formed on the body portion of the complementary coupler 4, the latter being likewise provided with an arm 5 overlapping and engaging a lug or projection 6 formed on the coupler member 4. Each of the complementary 55

parts of the coupler is provided with the usual nozzle or neck 7 which is adapted to be attached to a section of flexible hose extending from the train pipe at the end of the car, and a passage 8 extends through the body portion of each coupler, said passage-ways meeting and registering in the face portions 9 and 10 of the complementary parts when they are in locked condition as shown, suitable gaskets, as at 12, being provided to effect a tight joint. The coupler members when locked are supported by the flexible hose sections between the cars, which hose sections hang in a catenary curve, the construction being such that, should the cars draw apart when the coupler members are in locked condition, the coupler members will be automatically uncoupled by the upward swinging movement due to the tautening of the hose.

In hose couplers of the "Sewall" type, such as above described, it has been found desirable to provide means for preventing the relative rocking movement of the coupler parts when the coupler is subjected to strains that are due to the ordinary relative lateral movements of adjacent car platforms, such as are produced, for instance, in the rounding of reverse curves, which movements have a tendency to tauten the hose sections, thereby rocking the coupler parts and producing leakages, if not accidentally uncoupling them.

In order to prevent such relative movement of the coupler members as would tend to produce leakages or accidentally uncouple them, I mount upon each of the complementary parts a spring latch 11. In this preferred embodiment of my invention this spring latch is carried by an arm 13 mounted upon a pintle 14, extending from a lug 15, preferably cast integral with the coupler member, although this lug may be made separate therefrom and fastened thereto by means of bolts or rivets, if desired. This spring latch is adapted to swing transversely of the coupler member, and the outer end thereof is adapted to take over the side arm 2 or 5 of the complementary coupler when said complementary coupler parts are in locked condition, as shown in the drawings. An abutment 16 is formed upon each of the lugs, said abutments engaging the ends of the springs to hold them in engagement with the arms of the coupler members, or in positions removed therefrom; or, in other

words, abutment 16 operates to hold the spring latches on either side of a dead center position.

In the embodiment shown in Figs. 4 to 5, inclusive, of the drawings, the spring latch 11 is carried upon an arm 17 which is in turn pivotally supported upon a pin 18 fastened in the body of the coupler member, an abutment 20 cast integral with the body 10 of the coupler part being provided for cooperating with the spring latch. This abutment likewise operates to hold the spring latch in engagement with the arm of the opposite coupler or in a position disengaged therefrom.

Having thus described the construction of this embodiment of my invention, the operation thereof may now be understood. It should be understood that before locking 20 the reciprocal parts of the couplers, the swinging latch members are swung upward away from the bodies of the coupler members, so that the latter may be interlocked in the usual manner. The spring latches 25 are then swung about their points of pivotal support to the position shown in the drawings, in which each latch engages the arm of the opposite coupler. It will be seen that these latches will hold the coupler members 30 in their locked condition during ordinary conditions, but the strength of the springs is such that when the hose sections are subjected to undue strains the latches will yield to permit the coupler parts to automatically uncouple.

It will, accordingly, be seen that I have provided a construction adapted to attain among others all the ends and objects above pointed out, in a simple yet efficient manner. 40 The coupler members while held firmly in locked condition are nevertheless permitted to become automatically unlocked, thus rendering it impossible to break the hose sections in case the cars should become separated with the coupler parts in locked condition. It will be obvious, of course, that the spring latches, such as shown in the present construction, may be applied to existing couplers.

50 As many changes could be made in the above construction and many apparently widely different embodiments of this invention could be made without departing from the scope thereof, it is intended that 55 all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, 65 might be said to fall therebetween.

Having described my invention, what I claim as new and desire to secure by Letters Patent is:—

1. The combination with two parts of a hose coupling having means for engaging 70 and disengaging them, operative through relative rocking movements of said parts, of a spring locking member mounted to swing transversely and downwardly upon one of said parts adapted to engage the 75 other of said parts and oppose but not prevent a relative movement of said parts toward uncoupling.

2. The combination with two parts of a hose coupling having complementary locking means operative to lock and unlock said parts upon relative movements thereof, and auxiliary locking means located upon each part, comprising a spring member mounted to swing transversely and downwardly 85 thereon and engage the other thereof to oppose but not prevent such relative movement of said parts as will tend to uncouple them.

3. A direct port gravity hose coupler for 90 railway cars having a locking arm on one side with a locking projection on the opposite side, adapted to couple with its reciprocal coupler with a downward swinging movement and automatically to uncouple 95 with an upward swinging movement by a tautening of the hose as the cars draw apart, combined with a spring latch mounted to swing transversely and downwardly upon each of said couplers impositively engaging 100 the arm of the reciprocal coupler and resisting but not preventing an uncoupling movement.

4. The combination with a hose coupler having two complementary parts, a spring 105 latch mounted to swing transversely and downwardly upon each of said parts and engage the other thereof when said parts are in locked condition, and means for holding said spring latch in engagement with said part or disengaged therefrom.

5. The combination with a hose coupler having two complementary parts, each of which is provided with a locking arm on one side and a locking projection upon the opposite side adapted to couple by a downward swinging movement and to automatically uncouple by an upward movement, a spring latch mounted to swing upon each of said parts and swingable transversely and downwardly thereon into engagement with the arm of the complementary part, and means for holding said latch upon either side of a dead center position.

6. The combination with a hose coupler having two complementary parts each of which is provided with a locking arm on one side and a locking projection on the opposite side, said parts being mutually engageable and disengageable by a pivotal 125

- movement of said parts about a transverse axis, a spring latch pivotally mounted on a longitudinally extending pin upon one of said parts and adapted impositively to engage the other thereof, thereby resisting but not preventing the movement of said part toward uncoupling, and means for holding said latch in engagement with said part or disengaged therefrom.
- 10 7. The combination with a hose coupler having two complementary parts, each provided with a side arm overlapping and engaging with the other, a projection upon each of said parts with which one of said arms interlocks, a spring latch pivotally mounted upon each of said parts and adapted to swing transversely thereon into engagement with the side arm of the other part to hold said parts in locked condition
- 15 20 and to resist but not prevent an uncoupling movement thereof, and an eccentric abutment coöoperating with said spring latch to hold the same in positions of engagement with said arm or disengagement therefrom.
- 25 8. The combination with a gravity hose coupler for railway cars, comprising a pair of mutually engageable parts adapted automatically to disengage when the hose tautens as the cars draw apart, of a spring latch pivotally mounted upon each of said parts adapted to swing transversely thereon to engage the other of said parts to hold said parts in locked position and adapted to yield to permit said parts to become disengaged, and
- 30 35 an abutment having a dead center point over which the end of said spring latch is adapted to slide to hold said latch in or

out of engagement with the other of said parts.

9. The combination with a gravity hose 40 coupler having two complementary parts, each of which is provided with a side arm adapted to overlap and engage with the other, of a spring latch mounted upon one of said parts and adapted to swing trans- 45 versely thereon into engagement with the side arm of the other part, whereby said parts are held in engagement but are not prevented from becoming automatically disengaged when the hose tautens as the 50 cars draw apart, and an eccentric abutment formed adjacent the pivotal support of said latch adapted to be engaged by said latch to hold the same in a plurality of pivotal positions. 55

10. The combination of two parts of a hose coupling having complementary locking means operative to lock and unlock said parts upon relative movement thereof, an auxiliary locking means comprising an arm 60 mounted upon a longitudinal pivot upon one of said parts and a spring latch carried by said arm adapted upon the arm being swung downwardly, to engage the other of said parts and oppose but not prevent the 65 relative movement of said parts toward uncoupling.

In testimony whereof I affix my signature, in the presence of two witnesses.
